(57) **CLAIM**

The ornamental design for an electric screwdriver as shown and described.

DESCRIPTION

FIG. 1 is a top-front-right side perspective view of an electric screwdriver embodying my new design;

FIG. 2 is a bottom-rear-left side perspective view thereof;

FIG. 3 is a front elevation view thereof;

FIG. 4 is a rear elevation view thereof;

FIG. 5 is a left side elevation view thereof;

FIG. 6 is a right side view thereof;

FIG. 7 is a top plan view thereof;

FIG. 8 is a bottom plan view thereof; and,

FIG. 9 is an enlarged and partial perspective view thereof, wherein the area of enlargement is indicated as area 9 in FIG. 1.

The dot-dash broken lines do not represent any part of the actual subject matter and are not included in the claimed design. They are solely for annotative purposes, indicating the area of enlargement.

1 Claim, 9 Drawing Sheets
